UNITED STATES PATENT OFFICE.

JOSIAH M. READ, OF BOSTON, MASSACHUSETTS.

IMPROVEMENT IN RESERVOIR COOKING-STOVES.

Specification forming part of Letters Patent No. **152,048**, dated June 16, 1874; application filed March 13, 1874.

To all whom it may concern:

Be it known that I, JOSIAH M. READ, of Boston, in the county of Suffolk and State of Massachusetts, have invented certain new and useful Improvements in Cooking Stoves or Ranges; and I do hereby declare the following to be a full, clear, and exact description of the invention, such as will enable others skilled in the art to which it pertains to make and use it, reference being had to the accompanying drawings, which form part of this specification.

In the drawing, Figure 1 is a top view; Fig. 2, a vertical, central, and longitudinal section; and Figs. 3 and 4, front and rear side elevations of a stove embodying my improvements. Fig. 5 is a horizontal section thereof. Fig. 6 is a longitudinal section of the detachable stove-pipe, collar, and damper-plate; and Fig. 7 is a side elevation of the grate.

The nature of my invention consists in combining with a cooking stove or range, provided with a single oven, a deflecting-plate, arranged as hereinafter described, whereby the flame and volatile products of combustion are caused to pass around directly underneath the series of boiler-openings; also, in combining with the said deflecting-plate a damper and series of flues, arranged as hereinafter described, whereby the heat and volatile products are caused to pass entirely around the oven.

In the said drawing, A denotes the body of an ordinary stove, B being the top plate, and provided with boiler-openings C C, in the usual manner. D is the fire-box, and E the ash-pit, arranged directly underneath it. F is the grate, whose journals are suspended in the walls of fire-pot in the ordinary way. G is the oven, arranged in rear of the fire-box. H is a curved vertical plate, which is affixed to the rear part of the oven, and extends partially across the top thereof, and between the two rearmost set of boiler-openings, as shown by dotted lines in Fig. 1. I is a damper, also shown in dotted lines in said Fig. 1, such serving, when closed, in connection with the curved plate, to prevent the heat and volatile products of combustion from passing directly to

the smoke-exit, and causing them to pass down the diving-flue J and through the flue J' under the front part of the bottom of the oven; thence around the division-plate K into the flue L, under the rear part of the oven; thence into the ascending flue L'; and thence over the remaining part of the oven-top to the escape-port or smoke-pipe opening M. The left side of the oven being adjacent to the fire-box receives sufficient heat therefrom, and the entire draft-current from the fire passes through the flues and passages above mentioned around the oven, so that the oven is most thoroughly heated. But in kindling or quickening the fire, or when it is not desirable to use the oven, the damper I may be opened. In that case the heat, &c., are directed by the curved plate, so as to be carried around directly under the boiler-openings. N is the water-reservoir, which is disposed at the end of the stove adjacent to the fire-box. O is a rectangular or other proper shaped plate, which is fitted into an opening in the top plate of the stove, and so as to be flush with its upper surface. This plate has an opening, M, around which the stove-pipe collar s is formed. It also has a damper, P, affixed to its under surface, and so as to be capable of being moved back and forth over the opening M, so as to permit the draft to be regulated at pleasure. Furthermore, the opening M and collar s are located near one end of the plate, in order that by simply changing the plate end for end, the location of the stove-pipe may be better adapted to suit the desired position of the stove. R is a smoke-chamber, arranged on the rear part of the stove, as shown in Fig. 4. Within the outer vertical face thereof is an opening, e, corresponding in shape with the opening in the top plate before mentioned, such opening e being provided with a plate or cover, g, of the same form and size as the collar and damper plate O, the object of the opening e being to enable the collar and damper-plate O and the plate or cover g to be reversed, so as to permit the stove-pipe to be affixed to the rear part of the stove whenever desirable.

The stove, it will be understood, is to be

provided with a register for admitting air to the fire in the ordinary manner.

Having described the construction of my invention, what I claim is—

The combination, with a range or cooking stove, having a single oven, and a series of boiler-openings disposed over the same, of a deflecting-plate, H, damper I, diving-flue J, horizontal flues J' and L, ascending flue L',

and smoke-port M, substantially as and for the purposes stated.

In testimony that I claim the foregoing I have hereunto set my hand this 6th day of March, 1874.

JOSIAH M. READ.
